(57) **CLAIM**

The ornamental design for a fluid collection system, as shown and described.

DESCRIPTION

FIG. 1 is a perspective view of a fluid collection system showing my new design in a first position;

FIG. 2 is a perspective view of the fluid collection system in a second position;

FIG. 3 is a perspective view of the top piece of the fluid collection system in the second position;

FIG. 4 is a left side elevational view of the fluid collection system in the second position;

FIG. 5 is a rear, elevational view of the fluid collection system in the first position;

FIG. 6 is a front, elevational view of the fluid collection system in the first position;

FIG. 7 is a top view of the fluid collection system in the first position;

FIG. 8 is a bottom view of the fluid collection system in the first position;

FIG. 9 is a view of the fluid collection system in the first position taken along line 9-9 of FIG. 1; and,

FIG. 10 is view of the fluid collection system in the first position taken along line 10-10 of FIG. 1.
